JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,339,993.

Specification of Letters Patent. Patented May 11, 1920.

Application filed November 22, 1918. Serial No. 263,667.

To all whom it may concern:

Be it known that I, JOHN WALDHEIM, a citizen of the United States, residing at Elizabeth, in the county of Union and State 5 of New Jersey, have invented certain new and useful Improvements in Combined Typewriting and Computing Machines, of which the following is a specification.

This invention relates to improvements in 10 combined typewriting and computing machines, and especially to the kind known as the Underwood Addendograph disclosed in the application of Henry L. Pitman, Serial No. 24,390, filed April 28, 1915, (now Patent No. 1,308,506, dated July 1, 1919), in 15 which one or more totalizers traverse a relatively fixed master wheel; the totalizers being arranged to travel with the typewriter carriage; suitable tabulating mechanism, 20 comprising column-stops, being also provided.

More particularly the invention relates to punctuation space skipping devices for such machines.

25 In carrying out this invention, key-set column-stops are preferably used, and provision is made to set the column-stops to effective positions by a key in the keyboard of the machine, so that they may in one 30 of said positions control the escapement for double spacing by engaging with an intermediate actuating member to shift a dog-arresting element for the loose dog of the usual carriage escapement; each of the 35 column-stops being adapted to be engaged in either one of its effective positions by co-operative stops of the tabulating mechanism.

To set the column-stops to a plurality of 40 effective positions, the stop-setting key has variable movements, the extent of said movements being limited by a shiftable stop which normally permits the minimum depression of said key. When, however, the 45 carriage is moved to the decimal position in a computing zone, said stop is automatically shifted relatively to said key, so that when the stop-setting key is actuated while the carriage is in said decimal position, it is 50 moved through a greater extent, thus transferring a proportional amount of movement to the column-stop being set to bring it into range of the intermediate actuating member.

The shifting of the stop for the stop-setting key may be controlled by the carriage and preferably by the totalizers carried thereby, so that only the stops corresponding to the decimal positions of the totalizers may be set to an escapement controlling 55 position. To do this, each totalizer may be provided with a cam to engage with a suitable lever connected with the shiftable stop for the stop set key; the engagement between said cam and said lever taking place 60 when the decimal position of the totalizer is moved to a letter-space position corresponding to the printing point.

The intermediate actuating member, which 65 controls the arresting element for the loose dog of the escapement, is so positioned that it will be engaged only by the column-stops when they are set in their lowermost effective position, said actuating member being provided with a series of tappets or 70 cams corresponding in number to the number of punctuation positions in each totalizer, so that it may be actuated at said positions and thus move the loose dog-controlling stop, so as to permit a greater movement of the loose dog and consequently cause a double space movement of the typewriter carriage. Means are provided to move the intermediate member to an ineffective position when the computing mechanism is silenced, or, in other words, rendered 75 ineffective, which is done by means of the usual non-compute key. For this purpose, the stop-controlling element is pivotally supported on a pivoted frame, which is so 80 connected that it may be actuated by either the non-compute key or the case-shift key 85 thus to carry the intermediate member to an ineffective position.

Other features and advantages will hereinafter appear.

In the accompanying drawings, 90
Figure 1 is a sectional side view of the machine, showing the invention applied thereto, parts being in their normal positions.

Fig. 2 is a detail side view, showing a denominational stop actuated and in effective relation with one of the set column-stops; the stop-controlling member for the 105 loose dog of the escapement being shown as moved to its actuated position by the column-stop.

Fig. 3 is a view similar to Fig. 2 with the denominational stop in its normal position, and showing the stop-controlling member for the loose dog of the escapement as moved 5 to its ineffective position.

Fig. 4 is a skeleton perspective view of the invention and the associated parts.

Fig. 5 is a detail front view of the part 10 of the escapement mechanism showing the loose dog arrested by the stop member for single letter-spacing.

Fig. 6 is a similar view, showing the stop member shifted to arrest the loose dog for double spacing.

15 Fig. 7 shows a modified form of the invention, wherein the shiftable stop member, for limiting the movements of the stop-set key lever, is carried directly by said key lever.

20 Numeral keys 10 and alphabet keys 11 swing key levers 12 to rock bell-cranks 13 about a fulcrum 14 to swing type-bars 15 upwardly and rearwardly to cause types 16 to strike against the front side of the platen 18, the platen 18 being mounted on a carriage 19 which is adapted to be fed from right to left of the machine under the influence of a spring-drum 21.

To feed the carriage 19 step by step during 30 printing operations, each type-bar 15 is provided with a heel 22, which, during the latter part of the upward swinging movement of the type-bar, engages with a universal bar 23 to move the latter rearwardly 35 against the tension of a return spring 24, Fig. 4, said universal bar being provided with a cross-bar 25, which, during its rearward movement, engages with a dog-rocker 26 to move a loose dog 27 and a fixed dog 28 thereon between teeth 30 of an escapement wheel 31, thereby permitting step-by-step movement of said carriage 19, which is geared to said escapement wheel 31 by means of a rack 32 supported on said carriage, 40 said rack meshing with a pinion 33 having the usual one-way connection with said escapement wheel 31. During the rearward movement of the upper part of the dog-rocker 26, the loose dog 27 is moved out of 45 engagement with the escapement wheel, and is swung leftwardly about its pivot 34 to the position indicated in Fig. 5 by means of a spring 35, said dog 27 being arrested in this position by means of a stud 36 projecting rearwardly therefrom which engages with a stop 50 37 of a stop member 38. The escapement wheel 31 is at this time retained by the fixed dog 28 which has been moved into the path of the tooth 30 previously engaged by the loose dog 27. As soon as the universal bar returns to its normal position, the upper end 55 of the dog-rocker is moved forwardly by the spring 35, thus moving the fixed dog out of engagement with the escapement wheel 60 and the loose dog into the path of the next

tooth on the escapement wheel; said spring 35 being so disposed as to have a sidewise pull on the dog 27 and a forward pull on the dog-rocker 26. The escapement wheel is thus released and permitted to rotate until 70 the loose dog 27 strikes a fixed stop 40 at the upper end of said dog-rocker, Fig. 4, against which said dog normally is held.

The computing mechanism may be like that disclosed in the application of Henry 75 L. Pitman, Serial No. 24,390. The numeral keys 10 are adapted to rotate a master wheel 41 through digit distances equal from 1 to 9, inclusive. These movements of the master wheel may be transferred to dial wheels 80 42 by intermediate pinions 43, which are contained within the totalizer 44, adapted to travel with the typewriter carriage, so as to bring the intermediate pinions 43 *seriatim* into engagement with the master wheel 85 when the carriage passes through a computing zone. The totalizer may be adjustably supported on a bar 45 which may run on a rail 46 and may be connected to the typewriter carriage by means of one or more 90 arms 47 extending from the typewriter carriage.

To variably rotate the master wheel, the numeral keys are provided with plates 48 having cam slots 50 therein which vary in 95 shape, so as to rock a universal bail 51 through different angular distances according to the value of the numeral key; said universal bail forming part of a differential rocking frame 52 having a rock-shaft 53, 100 which serves as a fulcrum for said frame. Said frame has connected thereto a vertical link 54 which is pulled downwardly, when said differential frame is rocked, to rock a bell-crank 55 about its pivot 56 to drive 105 a rack 57 forwardly by means of a link 58, said rack 57 meshing with a pinion 60 to rotate a shaft 61 having secured thereto a gear wheel 62, which may mesh with any one of two pinions 63 and 64, to rotate the 110 master wheel 41 for addition and subtraction, respectively.

When the driving rack 57 has been moved forward an amount equal to the value of the actuated numeral key, it is permitted to 115 drop out of engagement with the pinion 60, so that it may be returned to its normal position. This may be done as disclosed in said Pitman application.

It will be seen by inspection of Fig. 4, 120 that the totalizer 44 is provided with three punctuation places, one between millions and hundreds of thousands, one between thousands and hundreds, and a decimal place between units and cents. Instead of 125 causing the operator to write these punctuation marks at these places while typing a number, provision is made to cause the carriage to feed two letter-space distances, thus skipping the punctuation places and leaving 130

blank spaces on the work-sheet where punctuation marks might have been written.

This may be done by devices on the carriage and preferably column-stops 65, which engage with a bail 66 having cams or tappets 67, one for each punctuation position. These tappets may be engaged when the carriage passes through a computing zone by the column-stops 65 to swing the bail about its pivot 68 against the tension of a suitable return spring 70. A forwardly projecting arm 71 of said bail 66 pulls upwardly on a link 72 connected to a rearwardly projecting arm 73 of the stop member 38, to swing the latter about its pivot 74 and bring a second stop 75 into effective relation with the loose dog 27, while the first-mentioned stop 37 is taken out of effective relation therewith. Thus the stop member 38 is shifted and held in its shifted position in the millions position, thousands position and units position. Upon typing the number in either one of these three positions, the universal bar 23 is again moved rearwardly to release the loose dog 27, which is at this time permitted to move leftwardly a greater distance to the Fig. 6 position where it is arrested by the rounded portion 76 of said loose dog which strikes the second stop 75 of said stop member. It will be seen by an inspection of Fig. 6 that the loose dog 27 has moved beyond the tooth 30 of the escapement wheel adjacent to the one previously engaged. Upon return of the dog-rocker to its normal position, however, the loose dog is moved into effective relation with the second tooth beyond the previously engaged tooth; thus the escapement wheel is permitted to move through a double tooth distance, and consequently the carriage feeds a double letter-space, thus skipping the punctuation position.

The column-stops 65 are of the usual key-set type, in which there is one stop for each letter-space position of the carriage, the stops being supported on a stop-bar 79 secured to the typewriter carriage. The column-stops 65 normally occupy their uppermost or ineffective positions. When it is desired to set the column-stops to an effective position, the carriage 19 is moved to the various columnar positions and may be positioned in each column by means of the usual scale and pointer, not shown. A stop-set key 77 is then actuated to swing a key lever 78 and rock a shaft 80 through the intermediary of a link 81 connected to an arm 82 extending from said shaft, the rock-shaft being provided with another arm 83, which pulls downwardly on a bar 84 having at its upper end a finger 85 which engages with the column-stop which happens to be thereunder, to depress the latter and move it to an effective position. The operator then moves the carriage to the next columnar po-

sition and proceeds to set another column-stop in the same manner. After all of the column-stops have been set, the carriage may be rapidly positioned in any denominational position of a column, by means of a 70 denominational tabulator having cooperative stops in the form of plungers 86 which may be moved upwardly into the path of the effectively set column stops by key levers 87 deppressible by tabulating keys 88. 75 When a tabulator key 88 is depressed, the plunger 86 actuated thereby engages a universal bar 90 to rock a shaft 91 and cause a downward pull of the link 92 connected thereto, thus swinging a release lever 93 about its pivot 94 to raise the rack 32 out of engagement with the escapement pinion 33, thus setting the carriage 19 free to be drawn leftwardly by the spring-drum 21 until one of the column stops 65 strikes the 80 actuated plunger or cooperative stop 86.

As hereinbefore described, the column-stops 65 control the double spacing, or, in other words, the punctuation spaces skipping of the carriage. The column-stops are 90 also used to position the carriage rapidly in places other than columns of figures, as, for example, in columns where articles are itemized. It will be seen that in the latter case there would be no need of skipping letter-space positions, and consequently provision is made in the present invention to permit the column-stops to be set in two effective positions, so that they may be engaged in either effective position by the cooperative 95 stops.

To set the column-stops in either of their effective positions, there may be a stop member 89 for limiting the depressions of the stop-set key 77. This stop member 89 may 100 be controlled by adjustable devices traveling with the typewriter carriage and preferably the totalizers 44, each totalizer being provided with a tappet 88^a which is effective, when the totalizer is moved with its 105 decimal place to a position corresponding to the printing point, to engage with a roller 90^a on a horizontal arm 91^a projecting laterally from the left-hand side of the frame of the machine, said arm forming 110 part of a swingable frame 92^a pivoted at 93^a and 94^a; the lower end of said frame having a forwardly projecting arm 95, which engages, by means of a pin-and-slot connection 96, with the pivoted stop member 89 to swing a stop 98 thereon out of the path of said key 77, so that it may be depressed through a greater extent to move the column-stop 65 to its lowermost effective position, and into effective relation with 115 the tappeted bail or carriage-feed controlling member 66.

It should be understood that the stop 98 is normally under the stop-setting key lever, and thus by the normal operation of said 120

key the column-stops 65 are set to their uppermost effective positions.

It is sometimes desirable to render the computing mechanism ineffective, or, in other words, silence the same so that the numeral keys 10 may be used to type numbers without actuating the computing mechanism. To do this, there is provided a non-compute key 100, which, when swung 10 forwardly about its pivot 101, moves rearwardly a link 102 connected to the lower end 103 thereof, to actuate a silencing device 104 secured to a rock-shaft 105 extending from side to side of the machine. Said silencing 15 device 104 comprises an arm 106 which engages with an interponent 107 forming part of the differential frame 52, so as to break the connection between the bail 51 and said differential frame proper; this connection 20 comprising a pin 108 on said bail 51 which projects laterally therefrom and lies in a notch 110 of said interponent; a spring 111 being provided to normally maintain said connection. It should be understood that 25 the bail 51 is loosely mounted on the rock shaft 53 and that it moves idly about the shaft 53 during numeral key actuations when the interponent 107 is out of engagement with said pin 108. The non-compute key 30 may be retained in any one of its positions by the usual detent or any other suitable means.

It is desirable to render the tapped bail or letter-feed varying means 66 ineffective 35 also and preferably when the computing mechanism is silenced. To do this, there is provided an upwardly extending arm 112 on the rock-shaft 105 to which the silencing member is secured. This arm 112 has connected thereto a link 113 which is drawn forwardly thereby to swing a frame 114 pivotally supported at 115 on the tabulator bracket. The upper end of said frame has pivotally mounted thereon the tapped bail 40 45 66, which is carried rearwardly and out of effective relation with the column-stops 65, Fig. 3. The bail 66 is guided in its movements from and to its ineffective position by the link 72 which swings about its point of 50 connection with the rearwardly projecting arm 73 of the stop member 38.

A modified form of this invention may be used as illustrated in Fig. 7, which shows the stop-setting key lever 78 provided at its 55 forward end with a pivoted stop member 116. Said stop member is provided with two keys 117 and 118. The stop member 116 is normally held against a stud 120 by means of a spring 121. The key 117 nearest 60 to the front of the machine is ordinarily actuated, and is arrested in its downward movement by a stop 122 engaging with a fixed stop 123; this movement of the key being sufficient to set the column-stop in

its uppermost effective position. When it 65 is desired to set a column-stop in its lowermost effective position, or, in other words, in its escapement controlling position, the key 118 is actuated which rotates the stop member 116 about its pivot 124 until it 70 strikes a stop 125. The key lever 78 is then moved downwardly until it is arrested by a stop 126 which strikes the fixed stop 123. It will be seen that with this arrangement the operator may selectively set the stop to 75 any one of the effective positions at will.

Variations may be resorted to within the scope of the invention, and portions of the improvements may be used without others.

Having thus described my invention, I 80 claim:

1. The combination of a carriage, a column-stop, actuating mechanism for said stop, and means controlled by said carriage to determine the extent of actuation of said 85 actuating mechanism to set said column-stop to any one of a plurality of effective positions.

2. The combination of a carriage, a column-stop on said carriage, actuating mechanism, including a key, for said stop, and means controlled by and actuatable at a predetermined point in the travel of said carriage to determine the extent of actuation of said actuating mechanism to permit said column-stop to be set to any one of a plurality of 95 effective positions by said key.

3. The combination of a carriage, a column-stop on said carriage, actuating mechanism for said stop, an adjustable member 100 on said carriage, and means controlled by said adjustable member to determine the extent of actuation of said actuating mechanism to set said column-stop to any one of a plurality of effective positions. 105

4. The combination of a carriage, a column-stop on said carriage, actuating mechanism for said stop, a totalizer, and means controlled by said totalizer to determine the extent of actuation 110 and actuating mechanism to set said column-stop to any one of a plurality of effective positions.

5. The combination with a carriage, of column-stops, a key to actuate said stops, limiting means for said key, and means to 115 automatically shift said limiting means to vary the movement of said key.

6. The combination with a carriage, of settable column-stops, a key to actuate said stops, and a movable stop-carrying device 120 engaging with said key to enable any one of said stops to be set in any one of a plurality of positions by said key.

7. The combination with a carriage, of column-stops on said carriage, a key, stop 125 setting means actuated by said key, stopping means for said key, and means actuatable by said carriage to shift said stopping means,

so as to permit variable movements of said key to set any one of said stops in any one of a plurality of positions.

8. The combination of a traveling carriage, a column-stop on said carriage, a key to actuate said stop, a totalizer adapted to travel with said carriage, a tappet on said totalizer, and means actuatable by said tappet to permit said column-stop to be set to any one of a plurality of effective positions by said key.

9. In a combined typewriting and computing machine, the combination of a carriage, column-stops, a key to set said column-stops, and means effective when the carriage is moved with the decimal place of a column to the printing point, to change the movement imparted to said stop by said key.

10. In a combined typewriting and computing machine, the combination of a carriage, a totalizer adapted to travel with said carriage, column-stops, a key to set said column-stops, and means effective when the totalizer is moved with its decimal place to a position corresponding to the printing point, to change the movement imparted to said stop by said key.

11. In a combined typewriting and computing machine, the combination of a carriage, a totalizer adapted to travel with said carriage, column-stops, a key to set said column-stops, and means effective when the totalizer is moved with its decimal place to a position corresponding to the printing point, to change the movement imparted to said stop by altering the extent of actuation of said key.

12. In a combined typewriting and computing machine, the combination of a carriage, a totalizer adapted to travel with said carriage, column-stops, a key to set said column-stops, means to vary the letter-feed movements of said carriage, and means effective when the totalizer is moved with its decimal place to a position corresponding to the printing point to change the movement imparted to said stop, so that said stop may be set into range of said letter-feed varying means.

13. In a combined typewriting and computing machine, the combination of a carriage, an escapement to control step-by-step feeding movements of said carriage, a totalizer adapted to travel with said carriage, column-stops, a key to set said column-stops, means engaging with said escapement to vary the movements of said carriage, and means effective when the totalizer is moved with its decimal place to a position corresponding to the printing point to change the movement imparted to said stop so that said stop may be set into range of said varying means.

14. In a typewriting machine, the com-

bination of a carriage, a totalizer adapted to travel with said carriage, column-stops, means including a key lever to set said column-stops, and a shiftable stop member to vary the actuation of said key lever, so that said stops may be set to a plurality of effective positions.

15. The combination of a carriage, column-stops, a coöperative stop, a carriage escapement, means to vary the feed of said carriage, a key, and means to control said key, so that said stops may be set in any one of two effective positions, so as to be engaged in both effective positions by the coöperative stop, said stops being effective when set in one of said effective positions to engage with the escapement-feed varying means.

16. The combination of a carriage, column-stops, a coöperative stop, a carriage escapement, means to vary the feed of said carriage, a key, means to control said key, so that said stops may be set in any one of two effective positions, so as to be engaged in both effective positions by the coöperative stop, said stops being effective when set in one of said effective positions to engage with said escapement-feed varying means, and means to render said escapement-feed varying means ineffective at will.

17. The combination of computing mechanism, silencing means therefor, a carriage, column-stops, a coöperative stop, a carriage escapement, means to vary the feed of said carriage, a key, means to control said key, so that said column-stops may be set in any one of two effective positions, so as to be engaged in both effective positions by the coöperative stop, said column-stops being effective when set in one of said effective positions to engage with said escapement-feed varying means, and a key to render said silencing means and said escapement-feed varying means ineffective at will.

18. The combination of a carriage, an escapement therefor, column-stops, means engaging with said escapement to vary the feed of said carriage, a key to set said column-stops, and means controlled by said carriage to permit said column-stops to be set individually into effective relation with said carriage-feed varying means.

19. The combination with a carriage, of a column-stop settable to a plurality of positions, a key, means actuated by said key to set said stop, and shiftable blocking means for limiting the movement of said key to different extents and thereby determining the setting of said stop upon depression of said key.

20. In a typewriting machine, in combination, a carriage, column-stops, a counter-stop, a carriage escapement, means to vary the action of said escapement, and means for yieldably supporting each of said

column-stops in an ineffective position and in two effective positions, each of said stops being positioned to engage said counter-stop when in either of said effective positions 5 and to engage said escapement-varying means when in one of said effective positions.

21. The combination of a carriage, a column-stop settable in an ineffective and two 10 effective positions, a counter-stop movable into position to be engaged by said column-stop in either of its effective positions, a carriage escapement mechanism, and means to vary the action of said carriage escapement mechanism positioned to be engaged 15 by said column-stop when the same is in one only of its effective positions.

22. In a typewriting machine, in combination, a traveling carriage, escapement 20 mechanism to effect letter-space feed movements of said carriage, means to vary the feed of said carriage, tabulating plungers, and column-stops, each adjustable to an ineffective and to two effective positions, said 25 column-stop being engageable by a projected plunger when set in either of its effective positions, and by said feed-varying means when in one of said effective positions.

23. In combination, computing mecha-

nism, a carriage, column-stops, each settable 30 to an ineffective and to two effective positions, a stop to coöperate with said column-stops when the latter are in either of their effective positions, a carriage escapement, means to vary the feed of said escapement, 35 said column-stops being effective, when set in one of their effective positions, to engage said escapement-feed-varying means, silencing means for said computing mechanism, and means whereby actuation of said 40 silencing means will render said escapement-feed-varying means ineffective.

24. The combination of a carriage, column-stops, each settable to an ineffective and to two effective positions, a coöoperative 45 stop effective, when actuated, to engage said column-stops when the latter are in either of their effective positions, a carriage-escapement, means to vary the feed of said escapement, actuated by said column-stops 50 when the latter are set in one of their effective positions, and means to render said escapement-feed-varying means ineffective.

JOHN WALDHEIM.
